DYEING APPARATUS

Edward J. Abbott, Wilton, N. H., assignor to
 Abbott Machine Company, Wilton, N. H., a
 corporation of New Hampshire

Application February 25, 1936, Serial No. 65,708

12 Claims. (Cl. 8—19)

This invention relates to dyeing apparatus and in its preferred form illustrated herewith embodies certain features which are disclosed also in my copending application Serial No. 463,649, filed June 25, 1930, now Patent Number 2,031,588. Among the several objects of the invention are to facilitate extraction of fluid from dyed, bleached or similarly fluid-treated material which is wound on perforated spools. My invention 5 may for example be used in the dyeing of wound yarn or top on perforated spools which are approximately 40 inches long and hold say 28 pounds net of the yarn or top. Such a spool 10 when soaking wet as the result of dyeing, will weigh 90 to 100 pounds, so that accordingly it is desirable to extract a large part of the liquid from the wound material before moving the spool. Also in many cases economies can be effected by saving such of the dye liquor, rinsing or bleaching 15 fluid as can be economically extracted from the wet spool, because of the fact that these fluids in many processes are not exhausted at the completion of one treatment of the number of spools held in a kettle at one time, and can be used 20 repeatedly. It is therefore more particularly an object of the invention to provide improved and simplified structure for extracting fluid from fluid-treated spools, in place in the kettle, at 25 slight cost, and without substantially complicating but on the contrary making use of the parts of the dye kettle useful in the dyeing or other fluid treatment. Accordingly in the preferred 30 embodiment of the invention now to be described, the dyeing apparatus in large measure acts to 35 separate the liquid from the exhausted air in the extracting operation.

Other objects of invention and features of advantage and novelty will be apparent from this 40 specification and its drawings, wherein the invention is explained by way of example.

In the drawings:

Fig. 1 is a vertical sectional view of a dye kettle according to this invention, parts of the apparatus being shown in elevation and parts being broken away for clearness of illustration;

Fig. 2 is a horizontal section taken on the line 2—2 of Fig. 1;

Fig. 3 is a detail to a larger scale than Fig. 2 showing the manner in which one of the slides is fitted to the vertical column;

Fig. 4 is a side elevation of the kettle of Fig. 1, from the opposite side, showing also the fluid supply conduits and storage tank;

Fig. 5 is a horizontal section on the line 5—5 of Fig. 4; and

Fig. 6 is a front elevation of a portion of a battery of dye kettles showing particularly their connection to a vacuum extractor; certain other connections of the kettles being omitted.

While my invention may be of more general utility, I regard it as particularly desirable in its illustrated embodiment in apparatus for spool dyeing yarn or the like, utilizing the features 10 claimed in my copending application Serial No. 463,649, now Patent No. 2,031,588. As disclosed in that application, the numeral 1 designates a dye vat or kettle having a bottom 2 and a false bottom 3 spaced from the bottom 2 to provide a 15 plenum chamber 4 between them. The false bottom 3 has a plurality of openings, each preferably provided with a tubular bushing sleeve 11, the lower ends of the sleeves resting upon the bottom 2, while the upper end of each sleeve or 20 bushing is provided with an annular seat-flange 7 adapted to support the lower end of a spool 6. The lower part of each bushing is provided with one or more elongate slots 12 permitting the flow 25 of fluid from the plenum chamber upwardly and into the hollow barrel of the spool resting upon the seat-flange 7 and thence outwardly through suitable perforations 14 in the spool barrel, so that liquid supplied under pressure to the plenum chamber flows out through the yarn or roving 30 wound upon the spool barrels.

A vertical rod 5, anchored at its lower end to the bottom 2, projects upwardly and axially through each bushing 11 and is provided with suitable means for clamping a spool 6 against the 35 corresponding seat 7. Such clamping means preferably comprises a retaining cap 8 or the like, adapted to bear against the top of the spool 6 and to close the upper end of the tubular spool barrel being held tightly against the upper end 40 of the spool by a nut 5^a engaging the screw threaded upper end of the rod 5.

The false bottom 3 is provided with a large opening 3^a preferably centrally located, and a vertically disposed hollow column 20 is arranged 45 to extend upwardly concentrically with this opening 3^a from the false bottom 3 to a point above the top of the kettle. Preferably this column consists of a plurality of aligned sections, the lower section which is within the kettle preferably being perforated, as indicated at 22, to serve as a strainer. The fluid within the dye kettle proper freely enters the column through these perforations and passes downwardly through the opening 3^a into the plenum chamber 4. At the 50 55

lower end of the column 20, I arrange a spider-like frame 23, which supports a suitable bearing 24 in which a vertical drive shaft 25 is mounted. This shaft preferably extends downwardly below the bearing and carries a suitable pump impeller 26^a at or near its lower end, such impeller preferably being arranged directly within the opening 3^a in the false bottom, the opening, if desired, being furnished with a lining sleeve or bushing 27. The pump impeller 26^a is preferably of the axial flow type, for example, a screw propeller, and the shaft 25 may be connected to any suitable (preferably reversible) driving means, for example, an electric motor 26 mounted upon the upper end of the column 20.

A part 40 (conveniently a metal casting) is arranged directly below the column 20 between the false bottom 3 and the true bottom 2 of the kettle, and acts to brace the central part of the false bottom and to support the weight of the column and parts carried thereby. This casting 40 preferably has a plurality of downwardly and outwardly curved ducts or passages 40^a having walls which tend to overcome any tendency of the liquid to swirl or take up a marked rotary motion within the plenum chamber. These passages compel the liquid to enter the plenum chamber in a plurality of independent and substantially horizontal streams, such passages communicating at their upper ends with the opening 3^a and at their lower ends with the plenum space 4.

A hollow frusto-conical portion 41 of the part 40 is arranged directly below the center of the pump impeller 26^a and defines the lower walls of the passages 40^a. A supply pipe 50 is arranged to deliver steam or other hot fluid into the chamber in part 41 and from this chamber ducts 42 lead outwardly to the passages 40^a, so as to deliver the hot steam into the fluid flowing through said passages 40^a, thereby heating the fluid without substantial tendency to produce hammer, and at the same time utilizing the kinetic energy of the steam for increasing the velocity of the flowing fluid. The plenum chamber is provided with a drain passage 56 controlled by a valve 51, which is operated through gears 52 and 53 and shaft 54 from a handwheel 55. The main body of the kettle is provided near its top with an overflow passage 57 connected to a vertical pipe 58 which extends down to below the kettle bottom.

The above apparatus is adapted for extracting of the dye or other liquid from the wound material as follows. Referring to Fig. 4, each kettle 1 is provided with an elevated storage tank 102, a motor-driven pump 103 and pipe connections 104 from the plenum chamber of the kettle and 105 to the storage tank, permitting the liquid contents of the kettle to be withdrawn through the pipe 104, pump 103 and pipe 105 to the storage tank 102 for future use. An inlet pipe 106 emptying into the kettle has valve controlled connections 107, 108 and 109 respectively leading from the storage tank 102, and from cold and hot water supplies.

Referring to Figs. 1 and 6, the connecting section 21 at the upper end of the vertical column 20 of each kettle is in open communication with the vertical column and is joined by a pipe 110 and valve 111 to a large diameter pipe 112 extending along the battery of dye kettles, and terminating at a liquid separator 113 and rotary vacuum extractor 114. Thus by means of the valve 111 of any one of the kettles, that kettle can have its connecting section 21 and vertical column 20 put into communication with the

vacuum extractor 114 and subjected to a suction of for example 4 inches of mercury.

Referring to Figs. 1, 2 and 3, the fluid openings 22 in vertical column 20, which normally serve to admit dye liquid into the column, are provided with valve means adapted to shut off the interior of the vertical column from the body of the dye kettle except by way of the plenum chamber 4 and interior of the spool barrels 6. As indicated, the column 20 is grooved to receive vertical strips 115 having openings 116 adapted to coincide with the openings 22 in the column, these strips being adapted to slide vertically so that their openings 116 are out of registry with the openings 22 which are then effectively closed against the entry of air or liquid. Upper and lower rings 119, 120 are arranged to confine the strips 115 to their slots, and a sliding ring 122 at the top of the strips 115 and connected thereto is adapted for use in lifting and lowering the strips simultaneously.

When the valve 111 is opened to connect a kettle with the vacuum extractor and the strips 115 are positioned to seal the openings 22 in the column, the plenum chamber 4 and interiors of the spool barrels of the kettle are subjected to vacuum which extracts the liquid from the wound material on the spools, and carries it to the plenum chamber 4 of the kettle where the air slows down and the moisture impinges on the bottom 2 of the kettle and separates from the air. The plenum chamber in this case is thus caused to serve as a liquid separator, the liquid being drawn off from the plenum chamber through pipe 104 and by the pump 103 to the storage tank 102, and the air continuing up through the passages 40^a, 3^a, past the impeller 26^a and up through the vertical column 20. The impeller 26^a need not be rotated during this extracting operation. The current of air passing the blades of this impeller is given a whirling motion which further drives entrained moisture out of the air. During the passage of the air current up through the central column, there is additional separation of the moisture, the moisture dropping down the column, and together with the other separated moisture being removed from the plenum chamber to the storage tank.

In order to restore the kettle to operating condition for dyeing, bleaching, or the like fluid treatment of the spool wound material, it is only necessary to shut off the vacuum valve 111, shut off the pump 103, move the ring 122 to position the openings 116 in registry with the openings 22, and run into the kettle the desired charge of treating fluid, through the pipe 106.

The invention is therefore especially adapted for repeated treatments of the same wound material by different treating agents, for example, a dyeing operation, a rinsing, and a second dyeing operation, with extraction of each liquid. This desirable result is attained, as will be seen from the above description, without complicating the dyeing apparatus, and particularly without sacrificing the advantage of the open-top kettle which is most convenient for the placing and removal of the spools of material.

It should be understood that the present disclosure is for the purpose of illustration only and that this invention includes all modifications and equivalents which fall within the scope of the appended claims.

I claim:

1. Dyeing apparatus comprising a kettle, a false bottom defining a plenum chamber in the lower part of the kettle, means for mounting

perforated spools of wound material in the kettle with their barrels in communication with the plenum chamber, a vertical column extending up through the kettle from the plenum chamber and having fluid openings affording communication between the body of the kettle and said column at various levels in the kettle, a fluid impeller associated with the lower part of the column, means for closing the fluid openings in the vertical column, and means for applying suction to the vertical column to extract moisture from the wound material.

2. Dyeing apparatus comprising a kettle, a false bottom defining a plenum chamber in the lower part of the kettle, means for mounting perforated spools of wound material in the kettle with their barrels in communication with the plenum chamber, a vertical column extending up through the kettle from the plenum chamber and having fluid openings affording communication between the body of the kettle and said column at various levels in the kettle, a fluid impeller associated with the lower part of the column, means for closing the fluid openings in the vertical column, means for removing liquid from the plenum chamber, and means for applying suction to the vertical column to extract moisture from the wound material.

3. Dyeing apparatus comprising a kettle, a false bottom defining a plenum chamber in the lower part of the kettle, means for mounting perforated spools of wound material in the kettle with their barrels in communication with the plenum chamber, a vertical column extending up through the kettle from the plenum chamber and having fluid openings affording communication between the body of the kettle and said column at various levels in the kettle, a fluid impeller associated with the lower part of the column, valves associated with the openings in the vertical column, said valves being adapted to close the vertical column off from the kettle except by way of the plenum chamber and spool barrels, and means for applying suction to the vertical column to extract moisture from the wound material.

4. Dyeing apparatus comprising a kettle, a false bottom defining a plenum chamber in the lower part of the kettle, means for mounting perforated spools of wound material in the kettle with their barrels in communication with the plenum chamber, a vertical column extending up through the kettle from the plenum chamber and having fluid openings affording communication between the body of the kettle and said column at various levels in the kettle, a fluid impeller associated with the lower part of the column, slide valves adapted to close the fluid openings in the vertical column, and means for applying suction to the vertical column to extract moisture from the wound material.

5. Dyeing apparatus comprising a kettle, a false bottom defining a plenum chamber in the lower part of the kettle, means for mounting perforated spools of wound material in the kettle with their barrels in communication with the plenum chamber, a vertical column extending up through the kettle from the plenum chamber and having fluid openings affording communication between the body of the kettle and said column at various levels in the kettle, a fluid impeller associated with the lower part of the column, strips adapted to coincide with the said fluid openings, said strips being slidable to block off said openings, and means for applying suction to the vertical column to extract moisture from the wound material.

cal column to extract moisture from the wound material.

6. Dyeing apparatus comprising a kettle, a false bottom defining a plenum chamber in the lower part of the kettle, means for mounting perforated spools of wound material in the kettle with their barrels in communication with the plenum chamber, a rotary fluid impeller and cooperating passage adapted to induce circulation of fluid through the spool barrels and material wound thereon, and vacuum extracting means having communication with the interior of the spools through said plenum chamber and arranged to draw air from the wound material past said fluid impeller, whereby the impingement of the air on the impeller acts to separate liquid from said air.

7. Dyeing apparatus comprising a kettle, means for vertically mounting perforated spools of wound material in the kettle, liquid-circulating means including a vertical column within and extending substantially throughout the height of the kettle, fluid connections between the bottom of the column and the interiors of the said spools, and extracting means connected to the upper part of the column, whereby during extraction of fluid from the wound material, the vertical column acts as a liquid separator.

8. Dyeing apparatus comprising a kettle, a false bottom defining a plenum chamber in the lower part of the kettle, means for mounting perforated spools of wound material in the kettle with their barrels in communication with the plenum chamber, means for inducing a circulation of fluid through the wound material and plenum chamber, means for closing off the plenum chamber from the body of the kettle except by way of the spool barrels, means for removing liquid from the plenum chamber, and a vacuum apparatus adapted to be put in communication with the plenum chamber, whereby a separation of fluid and air is effected in the plenum chamber in extracting fluid from the wound material.

9. Dyeing apparatus comprising a kettle, a false bottom defining a plenum chamber in the lower part of the kettle, means for mounting perforated spools of wound material in the kettle with their barrels in communication with the plenum chamber, means for inducing a circulation of fluid through the wound material and plenum chamber, means for closing off the plenum chamber from the body of the kettle except by way of the spool barrels, a fluid storage tank, means for withdrawing fluid from the plenum chamber to the storage tank, and a vacuum extracting apparatus arranged to be put into communication with the plenum chamber.

10. Dyeing apparatus comprising a kettle, a false bottom defining a plenum chamber in the lower part of the kettle, means for mounting perforated spools of wound material in the kettle with their barrels in communication with the plenum chamber, means for inducing a circulation of fluid through the wound material and plenum chamber, means for closing off the plenum chamber from the body of the kettle except by way of the spool barrels, a fluid storage tank, a pump for forcing fluid from the plenum chamber to the storage tank, and a vacuum extracting apparatus arranged to be put into communication with the plenum chamber.

11. Dyeing apparatus comprising a kettle, a false bottom defining a plenum chamber in the lower part of the kettle, means for mounting perforated spools of wound material in the kettle with their barrels in communication with the

plenum chamber, means for inducing a circulation of fluid through the wound material and plenum chamber, means for closing off the plenum chamber from the body of the kettle except by way of the spool barrels, a fluid storage tank, means for withdrawing fluid from the plenum chamber to the storage tank, a vacuum extracting apparatus arranged to be put into communication with the plenum chamber, and means for returning the fluid from the storage tank to the kettle.

12. Dyeing apparatus comprising a plurality of dye kettles each of which includes a false

bottom defining a plenum chamber in the lower part of the kettle and means for mounting perforated spools of wound material in the kettle in communication with the plenum chamber, a vacuum pump and connections whereby the vacuum pump can be put into communication with the plenum chamber of any one of the several kettles, storage tanks associated respectively with the individual kettles, and means for removing the liquid from the plenum chamber of each kettle to the associated storage tank.

EDWARD J. ABBOTT.
